UNITED STATES PATENT OFFICE.

WILLIAM H. GRAHAM, OF ST. LOUIS, MISSOURI.

DESIGN FOR A SINK-TRAP.

SPECIFICATION forming part of Design No. 22,237, dated February 21, 1893.

Application filed January 28, 1893. Serial No. 460,172. Term of patent 3½ years.

To all whom it may concern:

Be it known that I, WILLIAM H. GRAHAM, of St. Louis, Missouri, have invented and produced a new and original Design for Traps 5 for Sinks and Analogous Constructions, of which the following is a specification, reference being had to the accompanying drawings, making part of this specification, and in which—

- o Figure 1 is a side elevation of a trap showing my design, and Fig. 2 an edge elevation of the same, the two views being desirable to better illustrate the design.

The leading feature of the design consists 5 in the general form of the body of the trap.

A represents the body. It is substantially an oblate spheroid, but modified by the addition of the tubular portions B, C, and D, said portions B and C being at one end of said body, and said portion B at the opposite end 20 thereof, substantially as shown.

What I claim is—

The design for a trap herein shown and described.

WILLIAM H. GRAHAM.
